(57) **ABSTRACT**

The present disclosure provides a speaker including a frame, a vibration system, and a magnetic circuit system, wherein the vibration system includes a first vibration diaphragm and a second vibration diaphragm which are fixed to two opposite sides of the frame, the magnetic circuit system includes a bobbin, a magnet fixed in the bobbin and spaced from an inner wall of the bobbin, a first pole plate fixed on one side of the magnet close to the first vibration diaphragm, a second pole plate fixed to one side of the magnet close to the second vibration diaphragm, and a third pole plate fixed outside the bobbin and spaced from an outer wall of the bobbin. The first voice coil assembly and the second voice coil assembly move inside and outside in a staggered manner, which saves a Z-directional space of the speaker and achieves higher magnetic field efficiency.

SPEAKER

TECHNICAL FIELD

The present invention relates to the technical field of electroacoustic conversion, in particular to a speaker.

BACKGROUND

In the vehicle-mounted speaker industry, a traditional cone speaker is generally used, at present, automobiles have higher requirements for high sound quality, flexible layout, low power consumption, and small vibration of horns (speakers).

The vehicle-mounted speaker of the related art includes a frame, a vibration system fixed to the frame, and a magnetic circuit system with a magnetic gap, wherein the magnetic circuit system drives the vibration system to vibrate and produce sounds, the vibration system includes a vibration diaphragm fixed to the frame, and a voice coil assembly which is fixed to the vibration diaphragm and inserted into the magnetic gap to drive the vibration diaphragm to vibrate and produce sounds. However, this speaker has the problems of large structural size, low efficiency, and great low-frequency vibration.

SUMMARY

The present invention aims to provide a speaker for improving the magnetic field efficiency.

In order to achieve the above objective, the present invention provides a speaker comprising a frame, a vibration system fixed to the frame, and a magnetic circuit system with a magnetic gap, wherein the vibration system comprises a first vibration diaphragm and a second vibration diaphragm which are fixed to two opposite sides of the frame.

The magnetic circuit system comprises a bobbin which is opened along a vibration direction of the vibration system, a magnet fixed in the bobbin and spaced from an inner wall of the bobbin, a first pole plate fixed on one side of the magnet close to the first vibration diaphragm, a second pole plate fixed to one side of the magnet close to the second vibration diaphragm, and a third pole plate fixed outside the bobbin and spaced from an outer wall of the bobbin; and the first pole plate and the third pole plate form a magnetic bowl through the bobbin.

The magnetic gap comprises a first magnetic gap formed by the first pole plate and the third pole plate, and a second magnetic gap formed by the second pole plate and the third pole plate.

The vibration system further comprises a first voice coil assembly inserted into the magnetic gap to drive the first vibration diaphragm to vibrate and produce sounds, and a second voice coil assembly inserted into the magnetic gap to drive the second vibration diaphragm to vibrate and produce sounds.

Preferably, the bobbin comprises a bobbin bottom wall sleeved on an outer circumferential edge of the second pole plate in a spacing manner, a bobbin side wall extending in a bent manner from an inner circumferential edge of the bobbin bottom wall towards the first vibration diaphragm, and a bobbin extending wall which extends in a bent manner from the bobbin side wall towards a direction close to the first pole plate and is parallel to the bobbin bottom wall; and the bobbin extending wall is fixed to one side of the magnet close to the first vibration diaphragm.

2

Preferably, the third pole plate comprises a third pole plate side wall sleeved on the outer side of the bobbin side wall, and a third pole plate bottom wall which extends in a bent manner from the third pole plate side wall towards a direction close to the second pole plate and is parallel to the bobbin bottom wall; and the third pole plate bottom wall is fixed to the bobbin bottom wall.

Preferably, the bobbin extending arm is fixed to the magnet, the third pole plate bottom wall, and the bobbin bottom wall in a glued, riveted, or welded manner.

Preferably, the bobbin is made of a magnetically non-conducting material.

Preferably, the frame comprises a first frame for fixing the first vibration diaphragm and a second frame for fixing the second vibration diaphragm; the first frame is stacked on the second frame along a vibration direction of the vibration system; a mounting part is convexly arranged on one side of the first frame facing the second frame; an avoiding part matched with the mounting part is sunken in a position corresponding to the mounting part on the second frame; or, a mounting part is convexly arranged on one side of the second frame facing the first frame; and an avoiding part matched with the mounting part is sunken in a position corresponding to the mounting part on the first frame.

Preferably, the first frame comprises a frame body, a supporting part spaced from the frame body, and a plurality of frame extending arms extending from the frame body to the supporting part; a through hole that runs through the supporting part and fixes the magnetic circuit system is formed in the supporting part along the vibration direction; or, the second frame comprises a frame body, a supporting part spaced from the frame body, and a plurality of frame extending arms extending from the frame body to the supporting part; and a through hole that runs through the supporting part and fixes the magnetic circuit system is formed in the supporting part along the vibration direction.

Preferably, the first voice coil assembly comprises a first voice coil bobbin fixed to the first vibration diaphragm and a first voice coil wound on the first voice coil bobbin; the first voice coil is at least partially located in the first magnetic gap; the second voice coil assembly comprises a second voice coil bobbin fixed to the second vibration diaphragm and a second voice coil wound on the second voice coil bobbin; and the second voice coil is at least partially located in the second magnetic gap.

Preferably, the first voice coil bobbin further comprises a first leakage hole running through the first voice coil bobbin, and the second voice coil bobbin further comprises a second leakage hole running through the second voice coil bobbin.

Preferably, the first vibration diaphragm comprises a first dome located in the center, a first curved ring which surrounds the first dome and is fixed to the frame, and a first dome connecting wall formed by extending from the first dome towards the first voice coil assembly; the second vibration diaphragm comprises a second dome located in the center, a second curved ring which surrounds the second dome and is fixed to the frame, and a second dome connecting wall formed by extending from the second dome towards the second voice coil assembly; the first dome and the first dome connecting wall, and the second dome and the second dome connecting wall are integrated respectively;

the vibration system further comprises a first elastic wave assembly and a second elastic wave assembly which are fixed to the frame and are spaced from each other; one end of the first elastic wave assembly away from the frame is connected to the first dome connecting wall; one end of the second elastic wave assembly away from the frame is

connected to the second dome connecting wall; and the first elastic wave assembly and the second elastic wave assembly are in staggered distribution and have antiphase vibration.

The present invention has the beneficial effects: the speaker is provided, wherein the single magnet passes through the first pole plate, the third pole plate, and the second pole plate to form a closed magnetic field, thus forming the first magnetic gap and the second magnetic gap on the inner and outer sides of the bobbin. When under the same current, drive forces on the first voice coil assembly and the second voice coil assembly are the same, i.e., upper and lower BLs are the same. The first voice coil assembly and the second voice coil assembly move inside and outside in a staggered manner, which saves a Z-directional space of the speaker and achieves higher magnetic field efficiency.

BRIEF DESCRIPTION OF THE DRAWINGS

FIG. 1 is a schematic diagram of a three-dimensional structure of a speaker provided by the present invention.

FIG. 2 is a schematic diagram of an exploded three-dimensional structure of a speaker provided by the present invention.

FIG. 3 is a cutaway view of FIG. 1 along the A-A direction.

FIG. 4 is a schematic structural diagram of a magnetic circuit system provided by the present invention.

FIG. 5 is a cutaway view of FIG. 4 along the B-B direction.

FIG. 6 is a schematic diagram of an exploded three-dimensional structure of a magnetic circuit system provided by the present invention.

FIG. 7 is a schematic structural diagram of a first frame provided by the present invention.

FIG. 8 is a schematic structural diagram of a second frame provided by the present invention.

FIG. 9 is a schematic structural diagram of assembling of a first frame and a first vibration system provided by the present invention.

FIG. 10 is a schematic structural diagram of assembling of a second frame and a second vibration system provided by the present invention.

DETAILED DESCRIPTION OF THE EMBODIMENTS

The present invention is further described below in combination with the accompanying drawings and embodiments.

It should be noted that all directional indications (such as up, down, left, right, front, rear, inner, outer, top, bottom, . . .) in the embodiments of the present invention are only used for explaining relative position relationships between all components at a certain specific attitude (as shown in the figures). If this specific position changes, the directional indication also correspondingly changes with it.

Referring to FIG. 1 to FIG. 10, a speaker provided by the embodiments of the present invention is illustrated, which includes a frame 10, a vibration system 20, and a magnetic circuit system 30 with a magnetic gap. In particular, the magnetic circuit system 30 is configured for driving the vibration system 20 to vibrate and produce sounds. The frame 10 is configured for fixing the vibration system 20 and the magnetic circuit system 30.

Referring to FIG. 1 to FIG. 3, the vibration system 20 includes a first vibration diaphragm 21 and a second vibration diaphragm 22 which are respectively fixed on two

opposite sides of the frame 10, and the magnetic circuit system 30 is located between the first vibration diaphragm 21 and the second vibration diaphragm 22. In the speaker of the present invention, the first vibration diaphragm 21 and the second vibration diaphragm 22 on the two opposite sides are configured for producing sounds in a radiated manner. The vibration directions of the first vibration diaphragm 21 and the second vibration diaphragm 22 are opposite. Since a drive force provided by the magnetic circuit system 30 is the same, the vibration of the speaker can be offset.

Referring to FIG. 2 to FIG. 6, the magnetic circuit system 30 includes a bobbin 31 which is opened along the vibration direction of the vibration system 20, a magnet 32 fixed in the bobbin 31 and spaced from an inner wall of the bobbin 31, a first pole plate 33 fixed on one side of the magnet 32 close to the first vibration diaphragm 21, the second pole plate 34 fixed to one side of the magnet 32 close to the second vibration diaphragm 22, and the third pole plate 35 fixed outside the bobbin and spaced from an outer wall of the bobbin 31; and the first pole plate 33 and the third pole plate 35 form a magnetic bowl through the bobbin 31.

That is, the first pole plate 33 is stacked on a surface of one side of the magnet 32 close to the first vibration diaphragm 21, and the second pole plate 34 is stacked on a surface of one side of the magnet 32 close to the second vibration diaphragm 22.

The magnetic circuit system 30 provides a magnetic field through the magnet 32, and a closed magnetic field is formed via the first pole plate 33, the third pole plate 35, and the second pole plate 34, wherein the first pole plate 33 and the third pole plate 35 form the first magnetic gap 41, and the second pole plate 34 and the third pole plate 35 form the second magnetic gap 42. The second magnetic gap 42 and the first magnetic gap 41 are formed on the inner and outer sides of the bobbin 31.

The vibration system further includes a first voice coil assembly 23 inserted into the first magnetic gap 41 to drive the first vibration diaphragm 21 to vibrate and produce sounds, and a second voice coil assembly 24 inserted into the second magnetic gap 42 to drive the second vibration diaphragm 22 to vibrate and produce sounds.

In the speaker provided by the embodiments of the present invention, the single magnet passes through the first pole plate 33, the third pole plate 35, and the second pole plate 34 to form a closed magnetic field, thus forming the first magnetic gap 41 and the second magnetic gap 42 on the inner and outer sides of the bobbin 31. When under the same current, drive forces on the first voice coil assembly 23 and the second voice coil assembly 24 are the same, i.e., upper and lower BLs are the same. The first voice coil assembly 23 and the second voice coil assembly 24 move inside and outside in a staggered manner, which saves a Z-directional space of the speaker and achieves higher magnetic field efficiency.

Further, the bobbin 31 includes a bobbin bottom wall 311 sleeved on an outer circumferential edge of the second pole plate 34 in a spacing manner, a bobbin side wall 312 extending in a bent manner from an inner circumferential edge of the bobbin bottom wall 311 towards the first vibration diaphragm 21, and a bobbin extending arm 313 which extends in a bent manner from the bobbin side wall 312 towards a direction close to the first pole plate 33 and is parallel to the bobbin bottom wall 311; and the bobbin extending arm 313 is fixed to one side of the magnet 32 close to the first vibration diaphragm 21. Further, the bobbin is made of a magnetically non-conducting material, which may specifically be aluminum, copper, plastic, etc.

The third pole plate **35** includes a third pole plate side wall **351** sleeved on the outer side of the bobbin side wall **312**, and a third pole plate bottom wall **352** which extends in a bent manner from the third pole plate side wall **351** towards a direction close to the second pole plate **34** and is parallel to the bobbin bottom wall **311**; and the third pole plate bottom wall **352** is fixed to the bobbin bottom wall **311**.

Preferably, the bobbin extending arm **313** is fixed to the magnet **32**, the third pole plate bottom wall **352**, and the bobbin bottom wall **311** in a glued, riveted, or welded manner.

In the present embodiment, the first vibration diaphragm **21** includes a first dome **211** located in the center, a first curved ring **212** which surrounds the first dome **211** and is fixed to the frame **10**, and a first dome connecting wall **213** formed by extending from the first dome **211** towards the first voice coil assembly **23**; and the first dome **211** and the first dome connecting wall **213** are integrated.

The second vibration diaphragm **22** includes a second dome **221** located in the center, a second curved ring **222** which surrounds the second dome **221** and is fixed to the frame **10**, and a second dome connecting wall **223** formed by extending from the second dome **221** towards the first voice coil assembly **24**; and the second dome **221** and the second dome connecting wall **223** are integrated.

The first dome **211** and the first dome connecting wall **213**, and the second dome **221** and the second dome connecting wall **223** are injection-molded. The curved rings and elastic waves are connected, so that the vibration system **20** has better vibration balance.

The vibration system **20** further includes a first elastic wave assembly **25** and a second elastic wave assembly **26** which are fixed to the frame **10** and are spaced from each other; one end of the first elastic wave assembly **25** away from the frame **10** is connected to the first dome connecting wall **213**; one end of the second elastic wave assembly **26** away from the frame **10** is connected to the second dome connecting wall **223**; and the first elastic wave assembly **25** and the second elastic wave assembly **26** are in staggered distribution and have antiphase vibration.

In this embodiment, the first elastic wave assembly **25** and the second elastic wave assembly **26** are in staggered distribution and have antiphase vibration. By this structure, the first elastic wave assembly **25** and the second elastic wave assembly **26** make reasonable use of an internal space of the speaker, the height of the speaker is reduced, and thinning development is facilitated. Meanwhile, a double-vibration-diaphragm effective vibration area is realized, the vibration loudness of the speaker is improved to a large extent, and the acoustic performance is improved.

Referring to FIG. 1 to FIG. 3, the frame **10** includes a first frame **11**, and a second frame **12** stacked and fixed to the first frame **11** along the vibration direction of the vibration system **20**. The first frame **11** fixes the first vibration diaphragm **21**, and the second frame **12** fixes the second vibration diaphragm **22**.

Specifically, referring to FIG. 7, the first frame **11** includes a frame body **111** for fixing the first vibration diaphragm **21**, a supporting part **112** spaced from the frame body **111**, and several frame extending arms **113** extending from the frame body **111** to the supporting part **112**; and a through hole **114** that runs through the supporting part **112** and fixes the magnetic circuit system **30** is formed in the supporting part **112** along the vibration direction. Specifically, the magnetic circuit system **30** is fixed in the through hole **114** through the third pole plate **35**. Similarly, in other embodiments, the second frame **12** is provided with the above structures to fix

the magnetic circuit system **30**. That is, the second frame **12** includes a frame body, a supporting part spaced from the frame body, and several frame extending arms extending from the frame body to the supporting part; and a through hole that runs through the supporting part and fixes the magnetic circuit system is formed in the supporting part along the vibration direction.

In a production and assembling process, by the first frame **11** and the second frame **12**, after components of the vibration system **20** and the magnetic circuit system **30** are assembled, the vibration system and the magnetic circuit system are then fixed by a mortise and tenon joint structure or gluing, thus stacking and forming one complete frame **10**. This structure is favorable for saving assembling procedures and compressing the overall space of the speaker. Furthermore, this structure improves the fixing strength of the magnetic circuit system **30** and improves the reliability of the speaker.

A mounting part is convexly arranged on one side of the first frame **11** facing the second frame **12**; an avoiding part matched with the mounting part is sunken in a position, corresponding to the mounting part, on the second frame **12**. Similarly, in other embodiments, a mounting part is convexly arranged on one side of the second frame **12** facing the first frame **11**; and an avoiding part matched with the mounting part is sunken in a position, corresponding to the mounting part, on the first frame **11**.

The mounting part and the avoiding part on the first frame **11** and the second frame **12** are configured to realize their snap-in connection and horizontal positioning, so that a space required for combined connection between and horizontal positioning of the first frame and the second frame can be reduced. A larger accommodating space is provided for internal elements of the speaker, the thickness of the overall speaker is reduced, and the speaker is developed towards miniaturization.

Air vents are formed in a side wall of the first frame **11** and a side wall of the second frame **12**.

Each first elastic wave assembly **25** includes a first elastic wave fixing part **251**, a first elastic wave edge part **252**, and a first elastic wave connection part **253** for connecting the first elastic wave fixing part **251** with the first elastic wave edge part **252**; the first elastic wave fixing part **251** is fixed on the first frame **11**; and the first elastic wave edge part **252** is connected to the first dome connecting wall **213**.

Each second elastic wave assembly **26** includes a second elastic wave fixing part **261**, a second elastic wave edge part **262**, and a second elastic wave connection part **263** for connecting the second elastic wave fixing part **261** with the second elastic wave edge part **262**; the second elastic wave fixing part **261** is fixed on the second frame **12**; and the second elastic wave edge part **262** is connected to the second dome connecting wall **223**.

Cross sections of the first elastic wave connection part **253** and the second elastic wave connection part **263** along the vibration directions are waved. The waved elastic wave assemblies have higher vibration attenuation performance, which is conducive to improving the stability of vibration of the vibration system **20**, thus improving the product performance of the speaker.

In the present embodiment, four first elastic wave assemblies **25** and four second elastic wave assemblies **26** are included and are spaced from one another. Correspondingly, four first dome connecting walls **213** and four second dome connecting walls **223** are included. In other embodiments, the number of the first elastic wave assemblies **25** and the number of the second elastic wave assemblies **26** may also

be other numerical values. More preferably, the first elastic wave assemblies **25** and the second elastic wave assemblies **26** are located on the same horizontal plane.

The frame **10** further includes a fixing sheet **13** arranged between the first frame **11** and the second frame **12**; part of the first elastic wave assembly **25** is fixed between the first frame **11** and the second frame **12** through the fixing sheet **13**. Specifically, two centrosymmetric first elastic wave assemblies **25** include first connecting walls **254** and second connecting walls **255**. The first elastic wave edge parts **252** are connected with the first dome connecting wall **213** through the first connecting walls **255**, and the first elastic wave fixing parts **251** are bonded with the fixing sheet **13** through the second connecting walls **255**, so that the first elastic wave assemblies **25** are fixed between the first frame **11** and the second frame **12**. The fixing sheet **13** enhances the connection between the first elastic wave assemblies **25** and the first frame **11** as well as the second frame **12**. Similarly, in other embodiments, the second elastic wave assemblies **26** are provided with the above structures, so as to be fixed between the first frame **11** and the second frame **12**.

In the present embodiment, the first curved ring **212** includes a ringlike first curved ring main body **2121**, a first fixed part **2122** which extends in a bent manner from an outer circumferential side of the first curved ring main body **2121** and is fixed to the first frame **11**, and a first connection part **2123** extending in a bent manner from an inner circumferential side of the first curved ring main body **2121**; the first dome **211** is fixed to the first connection part **2123**; the second curved ring **222** includes a ringlike second curved ring main body **2221**, a second fixed part **2222** which extends in a bent manner from an outer circumferential side of the second curved ring main body **2221** and is fixed to the second frame **12**, and a second connection part **2223** extending in a bent manner from an inner circumferential side of the second curved ring main body **2221**; and the second dome **221** is fixed to the second connection part **2223**.

One side of the first dome **211** close to the magnetic circuit system **30** is fitted with several gaskets directly facing a first pole plate **33** and a third pole plate **35** (a bottom wall **352** of the third pole plate).

The first voice coil assembly **23** includes a first voice coil bobbin **231** fixed to the first vibration diaphragm **21** and a first voice coil **232** wound on the first voice coil bobbin **231**; the first voice coil **232** is at least partially located in the first magnetic gap **41**; the second voice coil assembly **24** includes a second voice coil bobbin **241** fixed to the second vibration diaphragm **22** and a second voice coil **242** wound on the second voice coil bobbin **241**; and the second voice coil **242** is at least partially located in the second magnetic gap **42**.

The first voice coil **232** is at least partially located in the first magnetic gap **41**, and the second voice coil **242** is at least partially located in the second magnetic gap **42**, thus generating an electromagnetic field together with the magnetic circuit system **30**, which realizes generation of a magnetic drive force and drives the first voice coil **232** and the second voice coil **242** to move in a reciprocating manner, so that the vibration diaphragm **20** vibrates in a reciprocating manner and produces sounds.

The first voice coil bobbin **231** further includes a first leakage hole **233** running through the first voice coil bobbin **231**, and the second voice coil bobbin **241** further includes a second leakage hole **243** running through the second voice coil bobbin **241**.

The first leakage hole **233** and the second leakage hole **243** are configured for improving the reliability of pressure relief during the vibration of the vibration system **20**. More

preferably, a plurality of first leakage holes **233** and a plurality of second leakage holes **243** are provided and are disposed at equal intervals, so as to realize pressure relief balance and improve the stability.

In the speaker of the embodiments of the present invention, referring to FIG. 9 to FIG. 10, in the vibration system **20**, a first vibration system is composed of the first vibration diaphragm **21**, the first voice coil assembly **23**, and the first elastic wave assembly **25**; the first vibration system is fixed on the first frame **11**; a second vibration system is composed of the second vibration diaphragm **22**, the second voice coil assembly **24**, and the second elastic wave assembly **26**; the second vibration system is fixed on the second frame **12**. The first vibration system and the second vibration system may be separately assembled and modularly manufactured.

The embodiments of the present invention are described above only. It should be noted that those of ordinary skill in the art can further make improvements without departing from the concept of the present invention. These improvements shall all fall within the protection scope of the present invention.

What is claimed is:

1. A speaker comprising a frame, a vibration system fixed to the frame, and a magnetic circuit system with a magnetic gap,

wherein the vibration system comprises a first vibration diaphragm and a second vibration diaphragm which are fixed to two opposite sides of the frame;

the magnetic circuit system comprises a bobbin which is opened along a vibration direction of the vibration system, a magnet fixed in the bobbin and spaced from an inner wall of the bobbin, a first pole plate fixed on one side of the magnet close to the first vibration diaphragm, a second pole plate fixed to one side of the magnet close to the second vibration diaphragm, and a third pole plate fixed outside the bobbin and spaced from an outer wall of the bobbin; the first pole plate and the third pole plate form a magnetic bowl through the bobbin;

the magnetic gap comprises a first magnetic gap formed by the first pole plate and the third pole plate, and a second magnetic gap formed by the second pole plate and the third pole plate;

the vibration system further comprises a first voice coil assembly inserted into the first magnetic gap to drive the first vibration diaphragm to vibrate and produce sounds, and a second voice coil assembly inserted into the second magnetic gap to drive the second vibration diaphragm to vibrate and produce sounds.

2. The speaker of claim 1, wherein the bobbin comprises a bobbin bottom wall sleeved on an outer circumferential edge of the second pole plate in a spacing manner, a bobbin side wall extending in a bent manner from an inner circumferential edge of the bobbin bottom wall towards the first vibration diaphragm, and a bobbin extending wall which extends in a bent manner from the bobbin side wall towards a direction close to the first pole plate and is parallel to the bobbin bottom wall; and the bobbin extending arm is fixed to one side of the magnet close to the first vibration diaphragm.

3. The speaker of claim 2, wherein the third pole plate comprises a third pole plate side wall sleeved on the outer side of the bobbin side wall in a spacing manner, and a third pole plate bottom wall which extends in a bent manner from the third pole plate side wall towards a direction close to the

second pole plate and is parallel to the bobbin bottom wall; and the third pole plate bottom wall is fixed to the bobbin bottom wall.

4. The speaker of claim 3, wherein the bobbin extending arm is fixed to the magnet, the third pole plate bottom wall, and the bobbin bottom wall in a glued, riveted, or welded manner.

5. The speaker of claim 1, wherein the bobbin is made of a magnetically non-conducting material.

6. The speaker of claim 1, wherein the frame comprises a first frame for fixing the first vibration diaphragm and a second frame for fixing the second vibration diaphragm; the first frame is stacked on the second frame along a vibration direction of the vibration system; a mounting part is convexly arranged on one side of the first frame facing the second frame; an avoiding part matched with the mounting part is sunken in a position, corresponding to the mounting part, on the second frame;

or, a mounting part is convexly arranged on one side of 20 the second frame facing the first frame; and an avoiding part matched with the mounting part is sunken in a position, corresponding to the mounting part, on the first frame.

7. The speaker of claim 6, wherein the first frame comprises a frame body, a supporting part spaced from the frame body, and several frame extending arms extending from the frame body to the supporting part; a through hole that runs through the supporting part and fixes the magnetic circuit system is formed in the supporting part along the vibration direction;

or, the second frame comprises a frame body, a supporting part spaced from the frame body, and several frame extending arms extending from the frame body to the supporting part; and a through hole that runs through 35 the supporting part and fixes the magnetic circuit system is formed in the supporting part along the vibration direction.

8. The speaker of claim 1, wherein the first voice coil assembly comprises a first voice coil bobbin fixed to the first vibration diaphragm and a first voice coil wound on the first voice coil bobbin; the first voice coil is at least partially located in the first magnetic gap; the second voice coil assembly comprises a second voice coil bobbin fixed to the second vibration diaphragm and a second voice coil wound on the second voice coil bobbin; and the second voice coil is at least partially located in the second magnetic gap.

9. The speaker of claim 8, wherein the first voice coil bobbin further comprises a first leakage hole running through the first voice coil bobbin, and the second voice coil bobbin further comprises a second leakage hole running through the second voice coil bobbin.

10. The speaker of claim 1, wherein the first vibration diaphragm comprises a first dome located in the center, a first curved ring which surrounds the first dome and is fixed to the frame, and a first dome connecting wall formed by extending from the first dome towards the first voice coil assembly; the second vibration diaphragm comprises a second dome located in the center, a second curved ring which surrounds the second dome and is fixed to the frame, and a second dome connecting wall formed by extending from the second dome towards the second voice coil assembly; the first dome and the first dome connecting wall, and the second dome and the second dome connecting wall are integrated;

the vibration system further comprises a first elastic wave assembly and a second elastic wave assembly which are fixed to the frame and are spaced from each other; one end of the first elastic wave assembly away from the frame is connected to the first dome connecting wall; one end of the second elastic wave assembly away from the frame is connected to the second dome connecting wall; and the first elastic wave assembly and the second elastic wave assembly are in staggered distribution and have antiphase vibration.
